J. R. KEYTON

CIRCUIT MAKER AND BREAKER

Filed Dec. 24, 1924

UNITED STATES PATENT OFFICE.

JOHN R. KEYTON, OF DOTHAN, ALABAMA.

CIRCUIT MAKER AND BREAKER.

Application filed December 24, 1924. Serial No. 757,948.

My invention relates to improvements in circuit makers and breakers and more particularly to such as are of the float controlled type and adapted for use in connection with the crank case of internal combustion engines for giving a suitable alarm when the oil supply becomes low.

Briefly stated, an important object of the invention is the provision of a device of the character set forth which is very simple in construction, strong and durable, and which may be readily applied to an internal combustion engine without necessitating any changes or modifications in the construction thereof, the device being maintained in association with the engine by means of the same fastening members which are employed by the engine assembly.

Another object of the invention is to provide in a device of this kind a novel and improved support and actuating means for a movable contact member, which support is capable of being removed from the engine without necessitating the dismantling or removal of the entire device.

The invention further contemplates an adjustable means whereby a circuit may be made when the oil in the engine crank case has fallen to a predetermined level.

The above and other features of novelty which characterize my invention are pointed out with particularity in the claims annexed to and forming a part of this specification. However, in order that my improvements may be better understood reference should be had to the accompanying drawings forming a part of this specification and wherein I have illustrated what I now regard as a preferred embodiment of the invention, the same as here depicted being effective for short circuiting the ignition system of the engine by grounding the magneto plug with the frame of the engine when the oil has fallen to a predetermined level. It is to be understood, of course, that I do not intend to restrict myself to the invention as shown but reserve the right to make such modifications and changes as fairly fall within the subject matter claimed hereinafter.

In the drawings,

Figure 1 is a perspective view illustrating the application of my invention to a well known type of motor vehicle engine;

Fig. 2 is a view similar to Fig. 1 but in side elevation;

Fig. 3 is a detail in side elevation drawn to enlarged scale, and

Fig. 4 is a group perspective illustrating the co-acting arms and their support.

Referring specifically to the drawings, wherein like reference characters denote similar parts throughout, numeral 5 designates a motor vehicle crank case having the usual cover 6 which is fastened thereto by means of the bolts 7 passing through the marginal flanges 5^a and 6^a. The transmission cover door characteristic of engines of this type is denoted by the numeral 8, while 9 indicates the magneto plug. Inasmuch as the engine per se forms no part of the present invention, further description is unnecessary.

In applying the invention as shown in Fig. 1 the lowermost oil pet cock 10 of the crank case is screwed out and replaced by the tubular connection 11 which is substantially U-shaped in formation and is preferably composed of tubes connected by elbows. The free end of the connection 11 carries a T-coupling 12, one branch of which carries so a nipple 12^a which receives an elbow 13 in the free end of which is threaded a nipple 14^a extending from the bottom of a casing or reservoir 14. The lowermost oil pet cock which was removed for application of the connection 11 is screwed into the free branch of the T-coupling 12 where it is adapted to be used in the usual manner for ascertaining whether an ample supply of oil is in the crank case.

Fig. 2 clearly indicates that the position of the casing or reservoir 14 is such that its bottom part will be at substantially the same level as the crank case aperture in which the connection 11 is screwed. Within the casing 14 is located a float 15 having an elongated stem 15^a which extends upwardly through the removable top 16 of the casing and

through a tubular guide 17 which extends a substantial distance thereabove. The top 16 of the casing is preferably retained in place by means of machine screws 16^a, it being necessarily removable in order that the float may be positioned in the chamber.

The upper end of the float stem 15^a is threaded, as indicated at 15^b, this portion being provided with removable stops in the 10 form of nuts 16^b. Between the nuts 16^b is disposed the laterally turned apertured end 18^a of a metal strip 18, the upper end of which pivotally carries a link 19, to the free end of which there is pivotally secured 15 an arm 20 which is pivoted intermediate its ends as indicated at 20^a to one branch of a yoke-like member 21 having an intermediate eye 21^a, whereby it may be securely fastened to the crank case cover by one of the screws 20 8^a which hold the door 8 in place. A second arm 22 is pivoted intermediate its ends as indicated at 22^a to the free branch of the yoke 21, the outer end of said arm being designed for movement to contact with the 25 magneto plug 9. The inner end of this arm 22 is provided with a V-shaped formation 23 which is designed to receive the inner end of the arm 20.

From the foregoing description read in 30 connection with the accompanying drawings it will be apparent that when the crank case is amply supplied with oil the same will flow through the connection 11 into the casing or reservoir 14 and cause the float 15 with its stem, 15^a to rise, thus imparting through the elements 18 and 19 a downward rocking movement to the free or inner end of the arm 20 which acts upon the V-shaped formation 23 to elevate the outer end of the 40 arm 22 from contact with the magneto plug. The ignition system of the vehicle will now, of course, function in its usual manner. However, when the oil in the crank case has fallen to such a level that the bearings of 45 the engine will become damaged, the float within the casing 14, of course, falls, resulting in a movement the reverse of that just described to bring the end of the arm 22 into contact with the magneto plug for short circuiting the ignition system and preventing the engine from being run.

In order to firmly attach the casing 14 to the engine I have devised the bracket 24 having oppositely turned apertured ends 24^a and 24^b. As depicted in Fig. 1, the aperture of the end 24^a is designed for attachment beneath an apertured ear 25 extending from the lower portion of the casing 14, the connection being made between the same by 50 means of a screw. The end 24^b of the bracket is clamped against the crank case cover plate flange 5^a by means of the nut of one of the fastening bolts 7. It will thus be evident that the casing 14 will not be permitted to move in any direction and that the

bracket 24 together with the connection 11 forms a very simple and acceptable means of application of my apparatus. The top 16 of the casing 14 is substantially dome-shaped so as not to collect dust or dirt.

70

As previously intimated, the nuts 16^b permit adjustment of the metallic strip 18 so that the ignition system may be short circuited when the oil in the crank case is at a predetermined level. Obviously, adjustment 75 may be made to render the apparatus effective before the oil level has reached a dangerously low point in order that the driver may still proceed to a garage for replenishment of the oil supply. I have provided the rod 28 which is fastened to the arm 22 and extends upwardly through the floor board. By pulling this rod upwardly the arm 22 will be raised clear of the magneto plug and the ignition system will be permitted to function. Any suitable means 80 may be availed of for retaining the rod 28 in position to hold the arm 22 out of contact with the magneto plug.

85

Having thus described the invention, what 90 is claimed is:

1. In a fluid level controlled short-circuiting device for the ignition systems of internal combustion engines or the like, a yoke having an intermediate attaching eye for 95 the reception of a fastening element of the engine assembly whereby said yoke may be adjustably mounted upon the engine and clamped in a predetermined position, the lateral ends of said yoke being parallel and 100 formed with bearings, arms journaled upon said bearings, the adjacent ends of said arms operatively engaging each other for relative swinging movement, one of said arms having connection with a fluid level responsive device, and the other arm being actuated by said first arm to engage an element of 105 said ignition system when the fluid level reaches a predetermined point.

105

2. In a short circuiting device for the 110 ignition systems of motor vehicles, the combination of a bracket having a pair of spaced lateral bearings, arms mounted on said bearings and connected for relative swinging movement, one of said arms being designed 115 to engage a part of said ignition system, and said bracket having an apertured offset portion for the reception of an attaching element whereby said offset portion may be adjustably held in flat engagement with a 120 portion of an internal combustion engine or the like, the said offset portion extending in the opposite direction from said bearings whereby said arms will swing freely without engagement with adjacent parts of the 125 vehicle.

115

3. In a short circuiting device for the 130 ignition systems of motor vehicles, the combination of a bracket having a pair of spaced laterally bearings, arms mounted on said

bearings, one of said arms having a notch in its end in which the adjacent end of said other arm engages to connect the said arms for relative swinging movement in opposite directions in a common plane, one of said arms being designed to engage a part of said ignition system and said bracket having an apertured offset portion for the reception of an attaching element whereby said offset por-

tion may be adjustably held in flat engagement with a portion of an internal combustion engine or the like, the said offset portion extending in the opposite direction from said bearings whereby said arms will swing freely without engagement with adjacent parts of the vehicle.

In testimony whereof I affix my signature.
JOHN R. KEYTON.
